Primary Examiner — Mary Shannon Malley*Assistant Examiner* — Jennifer B Salazar(74) *Attorney, Agent, or Firm* — Daniel M. Cohn;
Howard M. Cohn(57) **CLAIM**

The ornamental design for an adjustable pet feeder as shown and described.

DESCRIPTION

FIG. 1 is a top, front, right perspective view of an adjustable pet feeder, shown in a first configuration;

FIG. 2 is a bottom, rear, left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front, right perspective view of the adjustable pet feeder of FIG. 1, shown in a second configuration; and, FIG. 10 a bottom, rear, left perspective view of the adjustable pet feeder of FIG. 1, shown in a third configuration. The broken lines in the drawings depict portions of the adjustable pet feeder that form no part of the claimed design.
